CUBING APPARATUS FOR CONCRETE BLOCKS
George Rappl, 62 Rock Beach Road, Rochester, N.Y.
Filed Sept. 5, 1963, Ser. No. 306,824
1 Claim. (Cl. 214—6)

This invention relates to the handling of concrete blocks, and more particularly to apparatus for "cubing" or stacking such blocks after they are removed from a drying kiln. The name cubing is applied because the blocks are stacked in cubes, or more broadly hexahedrons, for easier transport.

The manufacture of concrete masonry blocks usually comprises the mixing of clean, graded gravel with proper amounts of water and cement. The mixture is then compacted into a mold to form blocks of the desired shape. In the mold the top of the block is down, and while the blocks are still "green"—i.e., before they have completely hardened, the blocks are placed with their top faces down upon the shelves of the racks of the drying kiln until they are completely cured. The top sides of the blocks therefore tend to become smooth, while the other sides of the blocks retain a rough or slightly uneven appearance.

On a construction job, a mason mortars and sets the blocks so that the smooth side of each block (hereinafter called the face of the block) faces upwardly to provide a reference surface for his level. Because it is easiest, when removing blocks from the drying rack, for the laborer to slide them out and leave their faces down, it has been the practice heretofore, however, to stack or cube the blocks from the rack face downward; and that is the fashion in which concrete blocks are commonly shipped. When the blocks reach the job then and are delivered to the masons they are face down and the mason has to turn the blocks over by hand before mortaring them and setting them in place.

The need for the mason to turn each block over by hand before he mortars and sets it adds to the work of the mason and is tiring, time-consuming, and costly. It increases the labor and takes the time of a highly-skilled, highly-paid journeyman.

To avoid this time-consuming labor of the mason, machines have been built and marketed for taking the blocks from the drying racks and automatically turning them over and stacking them face side up so that, when a cube of blocks reaches the job, the blocks are already face side up, and the mason is saved from the task of inverting them. The automatic machines heretofore provided for stacking or cubing the blocks are, however, quite expensive and beyond the means of the ordinary local concrete block manufacturing plant. The job of stacking or cubing the blocks in the block making plant has remained therefore largely a manual operation, and an operation, moreover, in which the blocks have largely been stacked face downward.

Manual stacking or cubing often results in the chipping or cracking of blocks. The principal objection to manual stacking, aside from the difficulty of getting the stackers to stack the blocks face up, however, has been the amount of labor involved.

Heretofore four men have been required to cube the production off a single drying rack. Even the automatic machines require two men to operate them.

It is an object of this invention to provide apparatus for cubing concrete blocks after removal from the drying racks so that the blocks will be stacked face upwards.

Another object of the invention is to provide apparatus of this nature which will be much less costly than the machines heretofore provided for this purpose.

Another object of this invention is to provide apparatus of this nature which will be semi-automatic in operation and which will minimize the amount of manual labor required for cubing the blocks.

2

An additional object of this invention is to provide cubing apparatus which will substantially eliminate the chipping or cracking of blocks in the stacking thereof.

Other objects of the invention will be apparent herein-
5 after from the specification and from the recital of the appended claim, particularly when read in conjunction with the accompanying drawings.

In the drawings:

FIG. 1 is a fragmentary plan view of cubing apparatus made in accordance with one embodiment of this invention, and with parts thereof broken away;

FIG. 2 is a side elevational view of this apparatus;

FIG. 3 is a fragmentary front elevational view of this apparatus with parts thereof broken away;

15 FIG. 4 is a fragmentary sectional view taken along the line 4—4 in FIG. 2 and looking in the direction of the arrows;

20 FIG. 5 is a fragmentary side elevational view illustrating the stacking pallet pivoted into its stacking position; and

FIG. 6 is a fragmentary side elevational view of the apparatus and illustrating the turning platform in its discharge position.

The cubing apparatus illustrated comprises a frame 25 having a carriage mounted thereon to reciprocate horizontally and supported by rollers upon stationary rails or ways carried at opposite sides of the frame. Mounted on the carriage for limited pivotal movement between a horizontal loading position, and a stacking position in which it is 30 inclined downwardly beyond the rear edge of the carriage, is a flat loading pallet. Pivoted by trunnions between a pair of vertical posts at the discharge end of the frame is a turning platform. At opposite sides thereof the platform is provided with rails which align with the rails for 35 the carriage rollers, when the platform is in one limit position. The platform is also provided with a conveyor section comprising a pair of laterally spaced ways between which are rotatably mounted a plurality of conveyor rollers. This conveyor section is so disposed that 40 it projects vertically upwardly from the end of the platform remote from the carriage, when rails of the platform align with the roller rails of the carriage. Normally the platform is locked by releasable catches in this latter position.

45 In operation the carriage is first shifted to its loading position at one end of the frame, and the pallet is placed in its horizontal position where it registers with the discharge end of a conveyor used to transport cured concrete blocks face down from a nearby drying rack. The 50 operator slides the cured blocks off this conveyor onto the pallet until a rectangular layer of blocks is disposed thereon. The operator then pushes the carriage onto the then-aligned rails of the platform to advance the carriage toward the then vertically-disposed conveyor at the far 55 end of the platform. The operator then tilts the pallet upwardly so that the layer of blocks thereon slides off the pallet and into a vertical layer on the platform against the vertically disposed conveyor. The carriage is then returned to the loading end of the frame and another 60 layer of blocks is placed thereon, and the carriage is again moved rearwardly and tilted to stack this layer of blocks on the platform against the first layer. These steps are 65 repeated until a plurality of layers of blocks have been stacked on the turning platform.

As the pallet is tipped to move each layer of blocks onto the platform, the blocks are rotated 90 degrees, whereby the blocks are stacked on the platform with their smooth surfaces facing away from the then vertically disposed conveyor of the platform. When the desired cube 70 of blocks has been formed on the platform, the platform-holding means is released by the operator. The weight of the blocks on the platform then causes the platform to

be pivoted by gravity for slightly more than 90 degrees until its conveyor aligns with another conveyor which is provided to carry the block away from the machine. The stack of blocks then rolls face up onto this other conveyor and is carried away. After the stack has rolled off the turning platform, gravity causes the platform automatically to rotate back into its horizontal position, and the operator once again secures it in place with the releasable holding means, after which the above-described operations may be repeated to cube another set of blocks.

Referring now to the drawings by numerals of reference, my novel cubing apparatus comprises a base or frame 11 formed from a pair of laterally spaced, parallel channel irons 12 and resting upon three transverse channel iron feet 13. Supported above the base or frame 11 by pairs of vertical channel iron legs 14 and 15 are confronting horizontal channel iron roller trackways 16. Each of the channel irons 16 at its rear or inner end 21' (FIG. 2) is beveled off, that is, cut on the diagonal for a purpose to be described below.

The frame 12, feet 13, legs 14 and 15 and trackways 16 are all welded together.

Secured to the channel irons 12 between the legs 15 and the rear ends of the channel irons 12 are vertical channel iron supports 18 (FIG. 2). These project vertically above the channels 14 and 15. Each channel iron 18 faces outwardly, and adjacent its upper end has a relatively short section of channel iron 19 welded in confronting relation to it (FIG. 1). Mounted in aligned openings in the confronting angle irons 18 and 19 are trunnions 22.

Pivottally mounted on the trunnions 22 is a turning platform 30. The platform comprises two pairs of laterally spaced, and generally triangularly shaped bearing plates 23 (FIGS. 1, 2, 3 and 6), which are spaced from angle irons 18 by spacers 21 (FIG. 3), two pairs of diverging angle irons 24, and a pair of confronting channel irons 25. Each pair of the angle irons 24 is welded at one end to one pair of triangular plates 23 and each channel iron 25 is welded to the other ends of the associated pair of angle irons 24. The forward ends of channels 25 are beveled off at 17 (FIG. 6) to abut against the beveled surfaces 21' on the rear ends of the channel irons 16 when the turning platform is in lower position, (FIG. 2).

Bolted or otherwise removably secured to the channel irons 25, to extend transversely therebetween in spaced, parallel relation are a plurality of channel irons 27 whose upper surfaces are coplanar. At its rear end, the left end in FIG. 2, each channel iron 25 has removably secured thereto at right angles by screws 28, one end of a tubular beam 29, which is rectangular in cross section. Extending transversely between the beams 29, and rotatably journaled at opposite ends thereof in the beams are a plurality of spaced, parallel conveyor rollers 31. Each beam 29 is braced and supported from angle irons 24 by a pair of spaced, parallel channel irons 32, which at one end are welded or otherwise permanently secured to the associated channel iron 24, and which at their opposite ends are removably secured to the beams 29 by screws 33.

Welded to the bottoms of the channel irons 25 adjacent their beveled ends, and extending transversely therebetween is a reinforcing channel iron 34. In this there is welded an elongate I-beam 35 which is of a length to rest upon blocks 36 (FIG. 2) secured to the upper face of channel irons 12, when the turning platform is in its lowered position.

Welded to the outer face of each channel iron 25 approximately midway between its ends is a tubular sleeve 38 (FIGS. 4 and 6) which is rectangular in cross section. The upper end of one of the sleeves 38 (the sleeve disposed adjacent the left side of frame 11 as shown in FIGS. 3 and 4) is connected by an arcuate rail 37 to the sleeve 40 which is carried by the beam 29 on the corresponding side of frame 11. When the turning platform is disposed as shown in FIG. 2, each of the sleeves 38 is disposed vertically and registers at its upper end with the lower

end of a sleeve 39 which is rectangular in cross-section. The sleeves 39 are secured to the inner faces of channel irons 18 approximately midway of their heights.

Guided at its upper end for vertical sliding movement in each sleeve 39 is a bar 41 which has a downwardly depending latch portion 42 which is adapted to project downwardly and into the adjacent sleeve 38 (FIG. 4) to lock the turning platform 30 against pivotal movement in the position shown in FIG. 2. At its lower end each bar 41 is pivotally connected by a pin 43 to a link 44 (FIG. 2) disposed adjacent the bottom of frame 11. Each link 44 is fixed at its opposite end to one end of a horizontally disposed and transversely extending rocker shaft 45 (FIGS. 1, 2 and 3), opposite ends of which are rotatably journaled in the channel irons 12 approximately midway between the ends of the latter.

Fixed at one end to one end of the rocker shaft 45 (the right end as viewed in FIG. 3) is an operating lever 46. The lever 46 extends diagonally upwardly toward the front or loading end of the frame 11 (the right end as viewed in FIG. 2) and passes through a vertical slot 47 (FIG. 3) formed in a bracket 48, which is secured to and projects vertically upwardly beyond one of the channel irons 14. Adjacent the upper end of bracket 48 the slot 47 is enlarged slightly to form a lateral shoulder 49 (FIG. 3). The lever 46 is adapted to rest on shoulder 49 when the latching tongues 42 are operatively engaged in the sleeves 38 as shown in FIGS. 2 and 4.

Mounted to slide on the frame 11 is a carriage designated generally at 51. Carriage 51 comprises rear and front bars 52, 53 (FIGS. 1 and 3) secured in spaced, parallel relation by longitudinally-extending bars 54 and a diagonal strut 55. The bars 52 and 53 carry rollers 56 at their ends which travel in the channel trackways 16. Secured at one end to each bar 52 and extending upwardly and forwardly (toward the right in FIG. 2) therefrom is an angle iron 57. Each angle iron 57 is curved as at 58 intermediate its ends, and the forward ends of these bars are connected to a transverse channel iron 59, which is supported on two vertically disposed angle irons 60 that are secured to and project upwardly from bar 53.

Mounted to rock on the curved surfaces 58 of the angle irons 57 is a rigid, generally rectangular pallet 61 which comprises a rectangular sheet resting on and secured to a reinforcing rectangular angle iron frame 64. Positioned between the pallet and the angle irons 57 are elongate, flexible straps 62 (FIGS. 2 and 5). Each strap 62 is secured at one end to the upper, horizontal surface of one of the angle irons 57, and at its opposite end to the under side of the pallet 61 at a point spaced slightly forwardly of its rear edge. Fixed at opposite ends thereof to the under side of the pallet 61 and looping downwardly beneath the pallet, when the latter is disposed as shown in FIG. 2, are laterally spaced hand rails 63. Angle iron blocks 65 welded at opposite sides to the rear end of the pallet rest upon the upper ends of a pair of vertical bars 66, when the carriage 51 is disposed at the loading end of the frame as shown in FIGS. 1 and 2, thereby to support pallet 61 in a horizontal plane. The supports 66 are secured to and project upwardly from the channel irons 16 adjacent opposite sides of the frame. Secured to the upper face of the pallet 61 along one side edge thereof (the right edge as shown in FIG. 3) is a strap 67. Secured to the rear edge of the pallet 61 to project thereabove is a strap 69; and secured adjacent opposite ends of this strap are two tubular members 68 (FIGS. 1, 2 and 5), which are adapted to function as stops.

As shown by broken lines in FIGS. 1 and 3, one end of a conveyor 71, which is used to convey concrete blocks face down from the drying racks to the loading end of frame 11, is mounted to overlap the frame 11 and align with one side of the pallet 61, when the pallet is in its lower position (FIGS. 1 and 2). One end of a further conveyor 72 (FIGS. 1 and 2), which is adapted to convey the concrete blocks away from the frame 11, is

bolted to the rear discharge end of frame 11 (the left end in FIGS. 1 and 2).

In use, assuming that the parts of the apparatus are positioned as shown in FIGS. 1 to 4, the operator first slides concrete blocks off the conveyor 71 onto the horizontally disposed pallet 61, arranging them in a single, rectangular layer bounded at one side and at the rear by the straps 67 and 69. Then the operator pushes the carriage 51 rearwardly (to the left in FIG. 1) so that the pallet moves off the supports 66, so that the rollers 56 roll off of the guideway 16 and into the channel irons 25 which at this time are aligned with the channel irons 16. When the carriage has approached the uprights 29, the operator uses the hand bars 63 to tilt the pallet downwardly over the curved surfaces 58 (FIG. 5) until the layer of blocks on the pallet is deposited vertically against the rollers 31 carried by the uprights 29 and onto the horizontal upper surface of the slat or channel iron 27 which is immediately adjacent the uprights 29. The carriage 51 is then returned to the forward loading end of the frame; and the pallet is tilted back to its horizontal position (FIGS. 1 and 2).

The operator then repeats the operation of transferring blocks from conveyor 71 to the pallet, placing the blocks in rectangular formation on the pallet. When the pallet is again covered with blocks, the operator again moves the carriage rearwardly, and dumps it. Each succeeding layer of blocks is thus stacked vertically on platform 30 against the preceding layer.

The blocks are transferred from the conveyor 71 to the pallet 61 face downward just as they are received by the conveyor but as each layer of blocks is dumped from the pallet, the layer is rotated substantially 90° so that the smooth surfaces of the blocks on the platform 30 face away from the rollers 31.

The slats 27 of the platform are spaced apart a distance such that each slat supports a different vertical layer of blocks, successive vertical layers being supported by successive slots. The stops 68 engage the front face of a slat when the pallet is tilted and thereby help determine the proper positioning of the successive vertical layers of the blocks against one another.

When enough layers of blocks have been dumped onto platform 30, the operator disengages the lever 46 from the shoulder 49, and pushes the lever down so that the latches 42 (FIG. 4) are withdrawn from the upper ends of the sleeves 38. The weight of the blocks on the platform 30 then causes the platform to be tilted by gravity about the trunnions 22 (counterclockwise in FIG. 2) until the undersides of the channel irons 25 engage the resilient bumpers 74 (FIGS. 2 and 6) carried by brackets 73 that project rearwardly from the supports 15 at opposite sides of the frame and align with notches in the beam 35. During this tilting movement of the platform, the lower end of the latch 42 at the left side of the frame, as viewed in FIGS. 3 and 4, rides on the rail 37 (FIG. 6) until the sleeves 40 (FIGS. 2 and 6) register with the latches 42, at which time the latter drop into the sleeves 40 to hold the beams 29 in the position shown in FIG. 6. At this time the beams 29 at their free ends are inclined slightly downwardly from the horizontal, and are in registry with the rollers on the discharge conveyor 72, and the weight of the concrete blocks has been transferred from the channel irons 27 to the conveyor rollers 31. As the weight of the blocks shifts to the rollers 31, the latter cause the stacked blocks to roll as a unit on the discharge conveyor 12.

After the blocks have rolled from platform 30 onto conveyor 72, the lever 46 is once again depressed to disengage the latches 42 from the sleeves 40. The platform 30 then pivots by gravity automatically back into the position shown in FIGS. 1 and 2, and the latches 42 ride on the rail 37 until they drop back into the sleeves 38. The lever is then moved into locking position on the shoulder 49,

and the apparatus is once again in position to be loaded as above-described.

It will thus be seen that applicant has provided relatively simple and inexpensive semi-automatic cubing apparatus, which is capable of cubing the entire production of a conventional concrete block molding machine. Moreover, whereas it formerly took four men to do the cubing job, one man working alone with the apparatus of the invention can do the cubing, and, moreover, get all the blocks face up. One man in fact can cube blocks just as fast (up to 8,000 a day) as they are delivered from the drying kiln. Also, the operator does not have to lift blocks at any time during the cubing process, therefore obviating chipping of the blocks, and thus improving their overall quality. With applicant's apparatus, moreover, all the blocks are stacked face up before delivery so that the masons need not turn the blocks over before mortaring them in place. Moreover, in applicant's apparatus all the automatic motions are effected by gravity alone, thus reducing to a minimum the labor of cubing and also eliminating any need for employing expensive drive means for accomplishing the same motions.

Another advantage of applicant's apparatus is that it may be adjusted to accommodate differently sized blocks by securing the slats or channel irons 27 at lesser or greater intervals along the channels 25. Also, the screws 28 and 33 permit the beams 29 to be adjusted relative to the channels 25. If adjustment of the beams 29 should affect the balance of the members suspended from the trunnions 22, weights may be clamped to the beam 35 to cause these members to assume the positions shown in FIGS. 1 and 2 when the channels 27 are unloaded.

While the invention has been described in connection with a specific embodiment thereof, it will be understood that it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth, and as fall within the scope of the invention or the limits of the appended claim.

Having thus described my invention, what I claim is:

- Apparatus for cubing concrete blocks, comprising
- (a) a frame having a loading station adjacent one end thereof and a discharge station adjacent its opposite end,
  - (b) a carriage mounted on said frame and reciprocable between said stations,
  - (c) a pallet mounted on said carriage for receiving and supporting a layer of concrete blocks face down in a substantially horizontal plane on said carriage, when the latter is positioned at said receiving station,
  - (d) a platform having a conveyor projecting substantially perpendicularly from one end thereof,
  - (e) means mounting said platform on said frame at said discharge station to pivot between a first position in which said platform is disposed horizontally beneath said carriage with its conveyor projecting upwardly therefrom, and a second position in which said platform is disposed nearly vertically with said conveyor projecting from the lower end thereof,
  - (f) releasable means for holding said platform in said first position,
  - (g) said pallet being mounted on said carriage to pivot from a horizontal position downwardly over the side of said carriage, when the latter is moved toward said discharge station, thereby to cause the layer of blocks thereon to be tipped onto said platform with the bottoms thereof facing said conveyor, when said platform is in said first position, and
  - (h) said mounting means being operative, upon the release of said holding means, to cause said platform to pivot to said second position in response to the weight of the blocks positioned thereon, whereby the

- last-named blocks are transferred face up onto said conveyor, and
- (i) at least one tubular member secured to said platform adjacent one side of said frame,
  - (j) at least one further tubular member secured to said conveyor adjacent said one side of said frame, and
  - (k) a manually operable latch mounted on said frame for limited movement, and insertable into locking engagement with the first-named tubular member, when said platform is in its first position, and into locking engagement with said further member, when said platform is in its second position.
